UNITED STATES PATENT OFFICE.

ROY E. CARTZDAFNER, OF PASSAIC, NEW JERSEY, ASSIGNOR TO ROBERT MAGOR,
OF MONTREAL, QUEBEC, CANADA.

RAILWAY-DUMP-CAR CHUTE LOCK.

Application filed August 6, 1925. Serial No. 48,522.

The invention relates in general to railway dump cars of the type in which the car bed is arranged to be tilted to one side or the other of the track to discharge its load and the present disclosure constitutes a companion case with application entitled Air dump car chute, Serial No. 48,521, filed under even date (File No. 1307).

It is a usual practice as is disclosed in 10 the companion application to provide such dump cars with side aprons, extension pieces or chutes disposed along the side margins of the floor of the bed and hinged thereto so that they may be swung laterally 15 to form extensions of the floor to throw the material being unloaded out far enough from the track so that it is not deposited on the track bed. When the car body is in its normal position the side aprons or chutes 20 are withdrawn so that they do not project beyond the side margins of the car bed and assume a substantially vertical position.

In the companion application there was 25 featured a construction to permit a limited rocking of the bed without swinging the apron or chute beyond the outline of the car body. Such constructions, however, have the objection in that the depending 30 apron or chute tends to swing laterally while the car is running and this lateral swinging of the heavy aprons on each side frequently develop a synchronizing action 35 between the different parts with a resulting acquiring of a sidewise momentum which is very apt to deleteriously affect the car and eventually rack it to pieces.

Accordingly, the primary object of the 40 present disclosure is to obtain the advantages of the apron and chute construction 45 featured in the companion application in so far as simplicity of construction, ease of operation and the like are concerned, and, at the same time, to provide for the securing of the apron against swinging movement when the car body is in its normal righted position.

Another object of the invention is to provide a simple form of construction by means 50 of which the aprons are automatically locked against swinging movement as an incident of the movement of the chute into its normal vertical position.

As these aprons and chutes must necessarily be made of heavy construction in or-

der to withstand the strains to which such 55 members are subjected it would follow that any locking means for defeating a tendency of these heavy members to swing must necessarily be rigid, massive and reinforced to provide a high strain resisting 60 construction.

Another object of the invention is to provide a form of chute locking means capable 65 of withstanding the heavy duty to which such members must be subjected and at the same time to provide a construction and a disposition of parts so that the lightest possible form of locking means can be used and in which parts in addition to the conventional car parts necessary for this purpose have been reduced to a minimum.

Various other objects and advantages of 70 the invention will be in part obvious from an inspection of the accompanying drawings and in part will be more fully set forth 75 in the following particular description of one form of device embodying my invention, and the invention also consists in certain new and novel features of construction 80 and combination of parts hereinafter set forth and claimed.

In the accompanying drawings in which there has been illustrated only such parts of 85 the dump car as are necessary to an understanding of the invention, Figure 1 is a vertical cross section of a dump car to which the improvements herein featured are applied showing the normal position of the parts 90 in full lines and in dotted lines their position when the bed has been tilted to discharge the load to the right; and

Figure 2 is a detailed plan view looking 95 down upon one end of the apron and showing its locking connection with the stop on the adjacent end sill.

In the following description and in the 100 claims, parts will be identified by specific names for convenience of expression but they are intended to be as generic in their application to similar parts as the art will permit.

Referring to the drawings 1 indicates the car bed as a whole; 2 the floor thereof; and 3 and 4 the side gates.

The bed is longitudinally mounted upon 105 its longitudinal center line on a series of pivots 7 arranged at suitable intervals and supported by standards 8 mounted on the

center sill of the under frame of the car body and which frame is preferably composed of two fabricated beams 9. The center sill is supported in the usual way on 5 four wheel trucks of standard design, 10 indicating the wheels, 11 the axle and 27 one of the usual two end sills. Each end sill is provided at opposite ends thereof with a vertically extending stop 28 the rear face 10 of which is formed slightly curved as shown at 29 for a purpose hereinafter described.

Secured to the underside of the car bed and extending longitudinally thereof are two side sills 12 and adjacent to each of 15 said side sills is an intermediate sill 30. Each side sill serves as a support for a bracket 13 disposed transversely of the car immediately under the side margins of the floor 2. These brackets, a number of which 20 are provided at suitable intervals from one end of the car to the other are preferably riveted to the side sills 2 and are bolted to the marginal portion of the floor as is usual in such construction.

25 Suspended from the brackets 13 are hangers 17 pivotally connected by pivots 18 to the brackets 13. The hangers 17 are in the form of rugged castings and are designed so that when in normal position they together with the brackets 13 snugly fit between the side sill and the adjacent intermediate sill. The hanger castings 17 are provided on their rear sides, each with a shoulder 31, the upper side of which constitutes a stop face for engaging the underside of the intermediate sill 30 and thus prevents inward swinging of the castings and their associated parts. Secured to the hanger castings 17 and in spaced relation to 40 their pivotal connection 18 with the car body is a side apron or chute 16. The arrangement of these parts is such that when either apron 16 is turned into a position of substantial alignment with the floor of the bed, as indicated by dotted lines in the drawings, its inner or upper margin will move slightly under the adjacent margin of the floor or slightly offset from the same as shown in dotted lines in either case providing a continuous surface which preferably, though not necessarily, lies in the same plane as the floor of the car bed over which the material being discharged may flow. For moving the apron or chute 16 out to 45 the position indicated in dotted lines and holding it there when the body is tilted there is provided one or more vertically swinging thrust bars 21 disposed at suitable intervals along the car. The thrust bars at 50 each side have their outer ends connected with the adjacent apron 16, or rather with the hanger castings 17, by pivots 22 engaging the castings. The inner ends of the thrust bars 21 are connected by pivots 23 55 with the lower end of depending links 24.

The upper ends of said links are connected by pivots 25 with ears 26 projecting from the center sill construction of the car underframe. The car underframe is also provided with abutments 32 adapted to be engaged by the links 24 as indicated by the dotted lines in the drawing and thus limit the outward swing of the apron as shown in dotted lines at the right hand side of Figure 1.

Each end of the apron 16, or rather the casting 17 in rear of the same, is provided adjacent its lower edge with a finger 33 which is designed to move back of the curved face 29 of the stop 28 and to be held by the stop against outward swinging movement. Preferably the parts are so proportioned and arranged that the curved stop face constitutes in effect a wedge so that the swinging apron is held against swinging movement laterally between the fixed stop provided by the intermediate sill 30 and the wedge stop provided by the curved face 29.

In operation it will be understood that a tilting movement of the car body such as a movement to the right as indicated in dotted lines in Figure 1 will cause the links 24 to swing into engagement with the stop 32 and a continued movement of the car body will cause the apron or chute to assume its operative position projecting beyond the outline of the car body as shown in dotted lines and as is more fully described in the co-pending above identified application. When the car body is tilted back into its normal running position the righting movement of the car body will cause the chute to swing inwardly until it is stopped by its engagement with the adjacent intermediate sill. At the same time the finger projecting from the lower edge of the apron slides in back of the curved face on the stop forming part of the end sill and when the finger reaches the central portion of the curve the car body has reached its level position as shown in full lines in the drawing.

Considering the situation on the opposite, i. e., the elevated side, it is noted that the position of the chute relative to the car body has not been changed for the chute is supported in direct bearing engagement with its adjacent intermediate sill. The curved upper side of the stop 28 on the elevated side of the car permits the ready upward escape of the finger 33 and when the car body is restored to its normal righted position the curvature forming the upper portion of the stop will assist in guiding the elevated apron back into its locked position.

By means of a construction such as is disclosed it is possible to lock the apron or chute from lateral swinging movement but this locking will in no way effect either the

elevating or the depressing movement of the car body as it is tilted to and from its dumping position.

While I have shown and described, and 5 have pointed out in the annexed claims, certain novel features of my invention, it will be understood that various omissions, substitutions and changes in the form and details of the device illustrated and in its 10 operation may be made by those skilled in the art without departing from the spirit of the invention.

Having thus described my invention, I claim:—

1. In a dump car, the combination with a car bed mounted to tilt laterally to discharge its load and provided with a side gate, of a side chute pivotally suspended along a side margin of the bed below the gate and 20 adapted to be projected into position to form a lateral extension of the floor thereof, means actuated by the tilting of the bed to discharge its load to project said chute into operative position and means spaced from 25 the pivotal mounting of the chute and operative on the righting of the car bed into its normal position for automatically locking the chute in its suspended position to prevent swinging of the chute while the car is 30 moving.

2. In a dump car, the combination with a car body mounted to tilt laterally to discharge its load, of a side apron pivotally suspended along a side margin of the bed 35 and adapted to be projected into position to form a lateral extension of the floor thereof, a pair of stops beneath the car body engaging the apron at vertically spaced points for locking the apron in its normal inoperative 40 position to prevent swinging of the same while the car is moving, and means operating on the tilting of the bed in discharging its load to remove said apron from its locked position and to project the same into operative position forming an extension of the 45 floor.

3. In a dump car, the combination with a car bed, mounted to tilt laterally to discharge its load, of a side apron pivotally suspended from the bed, normally hanging vertically therefrom, and adapted to be projected into position to form a lateral extension of the floor thereof, means controlled by the tilting movement of the car bed for 50 moving said apron to and from its normal position from and into its projected position, and locking means engaging the apron in spaced relation to its pivot when in said normal position for securing the apron from swinging movement in one direction.

4. In a dump car, the combination with a car bed mounted to tilt laterally to discharge its load, of a side apron pivotally suspended from the bed, normally hanging vertically 55 therefrom, and adapted to be projected into

position to form a lateral extension of the floor thereof, means controlled by the tilting movement of the car bed for moving said apron to and from its normal position from and into its projected position, and means 70 for locking the apron from swinging movement comprising a stop for limiting the swinging movement in one direction, a second stop for limiting the swinging movement in the opposite direction, said locking 75 means being operable automatically on the movement of the apron into its normal vertically hanging position.

5. In a dump car, the combination with a car bed mounted to tilt laterally to discharge its load, of a side apron pivotally suspended from the bed, normally hanging vertically therefrom, and adapted to be projected into position to form a lateral extension of the floor thereof, means for preventing inward 80 swinging of the apron and means for preventing outward swinging of said apron when in its normal vertical position.

6. In a dump car, the combination with a tiltable car body, of an extension piece located at the discharge end of the car body floor, means for holding the extension piece in position in which it does not project beyond the car body, and mechanism operated by the tilting of the car body auto- 90

95 matically to release the same from said holding means and to project the extension piece upon the discharge edge, beyond such discharge edge and return the said extension piece to its normal position in operative engagement with said holding means when the car body is brought back to normal carrying position.

7. In a dump car, the combination with a support, a tiltable car body pivotally mounted on the support, a chute pivotally suspended from the bed of said car body and adapted to be projected into position to form a lateral extension of the floor thereof, means extending between the support and chute and controlled by the tilting of the car body for moving the chute to and from its operative position, and a pair of interengaging stops for securing the chute to the support to prevent swinging movement of the chute.

8. In a dump car, the combination with a support provided with a vertically extending stop having a curved inner side, a tiltable car body pivotally mounted on said support, a chute pivotally suspended from the car body at one side, means controlled by the dumping movement of the car body for swinging the chute into position projecting beyond the lowered side of the car body and 100 for returning the same into its normal suspended position, and means carried by the chute and adapted to be moved on the righting of the car body with wedging engagement with the curved inner side of the stop 105

- to secure the same to the support and thus prevent outward swing of the chute.
9. In a dump car, the combination with a support provided with a vertically extending stop having a curved inner side, a tilttable car body pivotally mounted on said support, a chute pivotally suspended from the car body at one side, means controlled by the dumping movement of the car body for swinging the chute into position projecting beyond the lowered side of the car body and for returning the same into its normal suspended position, means carried by the chute and adapted to be moved on the righting of the car body with wedging engagement with the curved inner side of the stop to secure the same to the support and thus prevent outward swing of the chute, and stop means forming part of the tilttable body adapted to be engaged by the chute for preventing inward swing of the same.
10. In a dump car, the combination of a tilttable car body including a side sill and an intermediate sill, a bracket secured to the side sill, a hanger pivoted to the bracket and provided with a stop face for engaging the intermediate sill to limit the inward swing of the hanger, a chute secured to the hanger and means controlled by the dumping movement of the car body for swinging the chute and its hanger to and from the engagement of the hanger with the intermediate sill.
11. In a dump car, the combination of a tilttable car body including a side sill and an intermediate sill a bracket secured to the side sill, a hanger pivoted to the bracket and provided with a stop face for engaging the intermediate sill to limit the inward swing of the hanger, a chute secured to the hanger, means engaging the chute adjacent its free lower edge for securing the same against swinging movement in the direction away from said intermediate sill, and means controlled by the dumping movement of the car body for swinging the chute and its hanger to and from the engagement of the hanger with the intermediate sill.
12. In a dump car, the combination of a tilttable car body, a chute pivotally suspended at one side thereof, means controlled by the dumping movement of the car body for moving the chute to and from its operative position projected beyond the car body, means adjacent the pivotal connection of the chute with the car body for limiting the inward swing of the chute and means adjacent the lower edge of said chute for limiting the outward swing of the same.
13. In a dump car, the combination of an end sill provided at one end with a vertically extending stop, a tilttable car body provided on one side with a chute, means controlled by the dumping movement of the car body for moving the chute to and from its operative position projecting beyond the car body, said chute provided at one end thereof with a finger adapted to be disposed on the righting movement of the car body in position in rear of said stop thereby to limit swinging movement of the chute in one direction.
14. In a dump car, the combination of a tilttable car body provided with a stop, a casting pivotally connected at its upper end to the car body and provided on its rear side with a shoulder adapted to engage said stop, to limit inward swing of the casting, a chute secured to the lower end of the casting and means for swinging the chute to and from the engagement of the casting with said stop.
15. In a dump car, the combination of a support, a tilttable car body pivotally mounted on said support, a chute pivotally suspended from the car body at one side thereof, and means operable when the car body is in normal righted position for securing the chute at two points each spaced from its pivotal connection with the support from swinging movement relative to the support while the car is running.

Signed at New York in the county of New York and State of New York this 31st day of July A. D. 1925.

ROY E. CARTZDAFNER.
